TOP FOR TRUCKS AND THE LIKE

Stanley F. Walden, Newton, Mass.

Application December 18, 1936, Serial No. 116,487

3 Claims. (Cl. 296—105)

This invention relates to tops for trucks or like vehicles which comprise a canopy or tilt, and the object is to provide a simple, efficient and readily manipulable device capable of a wide 5 range of adjustment to a multiplicity of positions to meet the varying demands of use, such capability adapting it more particularly to the requirements of military use although not limiting it in any way thereto.

10 My invention will be well understood by reference to the following description taken in connection with the accompanying drawings, wherein:

Fig. 1 is a side elevation of a truck having a body construction illustrative of the invention showing the parts in one position of adjustment;

Fig. 2 is a similar view showing the parts in another position of adjustment;

Fig. 3 is an enlarged broken detail in side elevation; and

Fig. 4 is a partial transverse section on a smaller scale.

Referring to the drawings, I have there shown a truck having a wagon-box 6 which in the example shown is of a box-like form in the popular sense of that word, having an open top adapted to be covered over by the canopy or tilt. On the sides of the wagon-box at the front and rear ends thereof and remote from the rear wheel 20 housing 8 I may secure sockets 10 preferably in the form of open-ended rectangular tubes in which telescope for vertical sliding movement therein posts 12 which likewise may be in the form of rectangular tubes and which, through suitable bracket fittings 14, support longitudinal rails 16 paralleling the sides of the wagon body. To provide for vertical adjustment of the rails 16 the sockets 10 may be provided with suitable holes 18 and the posts 12 each (see Fig. 4) with a series 40 of holes 20 adapted to mate therewith in different positions of elevation of the post relative to its socket and a removable pin 22 passing through the holes 18 may engage one or another of the holes 20. I also prefer to provide a set screw 24 in the wall of socket 10 to be set up against post 12 to secure it firmly in position and avoid any rattling. By virtue of the adjustment thus provided the rails 16 may be supported either in a lower position, shown in Fig. 1, closely adjacent 50 and paralleling the sides of the wagon-box, or in one or more elevated positions, such as that illustrated in Fig. 2.

The rails 16 support the tilt-supporting bows 26 which (see Fig. 4) have substantially parallel leg portions adapted to straddle the rails 16 and

the box 6. These legs work in vertical sockets formed in fittings 28 adapted to slide along the rail as described in my Patent No. 1,679,642, dated August 7, 1928, to which reference may be made for a fuller description of these parts. As 5 described in this patent, the bows may be vertically adjusted by sliding the legs in the fitting and they are retained in one or more of a series of adjusted positions by means of a retaining pin carried by the fitting and engaging one 10 or another of a series of vertically spaced holes 30 in the post (Fig. 4).

In the elevated position of the rails 16, as shown in Fig. 2, the tilt has a number of positions of vertical adjustment corresponding to the number 15 of openings 30 provided and it may be either extended as shown in that figure to cover the length of the wagon-box or collapsed by a relative sliding movement of the bows to uncover more or less of the wagon-box. By the movement of the 20 posts 12 in the sockets 10 an adjustment is also provided independent of the adjustment of the bows vertically on the rails 16. In particular there is thus provided the extreme low position shown in Fig. 1 wherein only substantially the 25 curved portions of the bows project above the sides of the wagon-box. In all positions of the bows they may be either collapsed together or extended so that the tilt covers the box. In Fig. 1 I have shown the bows collapsed together but 30 they might be drawn out to the same relative horizontal spacing, as illustrated in Fig. 2. For military use it is desirable to have the silhouette of the truck as low as possible. When unloaded it may be desirable to cover it with branches or 35 other camouflage, and such concealment is facilitated by the provision of bringing the parts to the position of Fig. 1.

While the construction shown provides a wide range of vertical adjustment, the legs of the bows 40 are nevertheless relatively short. This not only makes them light and wieldy but permits their movement to and in the position of Fig. 2 without interference from any chassis elements located adjacent the rear axle. On the other hand, 45 the posts 12, as shown in Fig. 1, move into free spaces at the ends of the wagon-box but have a relatively limited range of movement as compared with the range of movement of the tilt as a whole so that they do not at any time project to 50 an objectionable degree below the floor of the box.

The canvas cover or tilt 32 is supported by the bows 26. In Fig. 2 I have shown one side of this cover as reefed or furled. It will be understood that the edges of the cover should be capable of 55

extending over the sides of the wagon-box 6 in the most elevated position of the former, the edges being secured by tie ropes 34 in the usual manner. To dispose of the marginal portions of 5 the cover when in the lower positions of adjustment and also to permit reefing up one or both sides in the manner illustrated in Fig. 2, I may dispose above the points of attachment of the tie ropes 34 grommets 36, the spacing of which 10 conveniently corresponds to the intervals of adjustment provided in the supporting mechanism. The tie ropes may be reeved through the grommets in the manner of earings to draw the margin up to the line of the grommets and to 15 serve as gaskets for furling and securing the resulting bunt as illustrated in Fig. 2. In lowered positions of the top the ends of the tie ropes remain available to secure the thus furled margins to the sides of the wagon-box in the 20 usual manner.

Referring to Fig. 3, the supporting pin 22 is here shown as forming the shank of a socket wrench 38 adapted to fit the head of set screw 24 and this wrench is connected by a flexible 25 chain 40 to a collar 42 rotatably fixed to the set screw 24. In adjusting the post 10 the shank 22 of the wrench may be used as a lining up pin. Then normally the screw 24 would be set up 30 finger-tight, after which the pin could be withdrawn and the wrench used to set up the screw, after which the shank 22 would be returned in 35 position to support the post under strains of travel. While the scope of the chain 40 provides freedom for manipulation of the parts, loss is prevented even in the example shown wherein they are merely connected together since the pin and the set screw will never in normal use be removed at the same time.

I am aware that the invention may be embodied in other specific forms without departing 40 from the spirit or essential attributes thereof, and I therefore desire the present embodiment to be considered in all respects as illustrative and not restrictive; reference being had to the 45 appended claims rather than to the foregoing description to indicate the scope of the invention.

I claim:

1. A body construction for trucks and like vehicles comprising a box, tubular sockets at the

sides of the box, posts vertically movable in the sockets, longitudinal rails carried by the posts, means for fixing the posts in a plurality of adjusted positions to support the rails at substantially different elevations from the floor of the 5 body, tilt-supporting bows of a width to span the box having parallel leg portions and fittings supported by the rails in which said leg portions telescope and means for securing the bows in a plurality of substantially differing positions of 10 vertical adjustment in said fittings.

2. A body construction for trucks and like vehicles comprising a box, tubular sockets at the sides of the box, posts vertically movable in the sockets, longitudinal rails carried by the posts, 15 means for fixing the posts in a plurality of adjusted positions to support the rails at substantially different elevations from the floor of the body, tilt-supporting bows of a width to span the box having parallel leg portions and fittings supported by the rails for longitudinal sliding movement therealong, in which fittings said leg portions telescope and means for securing the bows in a plurality of substantially differing positions of 20 vertical adjustment in said fittings. 25

3. A body construction for trucks and like vehicles comprising a box, tilt-supporting bows of a width to span the box having parallel legs, longitudinal rails extending along the sides of the box, means for supporting said rails adjustable to position them in a plurality of substantially differing vertical positions, fittings slideable along said rails to provide for extension of the tilt over the box or collapse thereof, said fittings having means for supporting the legs of the bows with 30 provision for vertical sliding movement thereof relative to the rail and permitting the disposition of the ends of the legs outward of the sides of the box and below said rails, and means for supporting the bows in a plurality of substantially different positions of vertical adjustment in the fittings 40 whereby a total range of vertical adjustment of the tilt for any position of longitudinal extension or collapse thereof is provided substantially in excess of the length of the legs of the bows without interference with portions of the vehicle 45 adjacent the lower portion of the box.

STANLEY F. WALDEN.
